CLAIM

The ornamental design for a gateway, as shown and described.

DESCRIPTION

FIG. 1 is a top, front, and right side perspective view of a gateway showing our new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a top, front, and right side perspective view in an opened condition.

The broken lines in the figures show portions of the gateway that form no part of the claimed design.
